UNITED STATES PATENT OFFICE.

CHARLES REINEKE, OF NEW YORK, N. Y., ASSIGNOR TO THE REINEKE MOTOR CORPORATION, OF NEW YORK, N. Y., A CORPORATION OF DELAWARE.

INTERNAL-COMBUSTION ENGINE.

Application filed December 29, 1921. Serial No. 525,701.

To all whom it may concern:

Be it known that I, CHARLES REINEKE, a citizen of the United States, residing at New York, in the county of New York and State of New York, have invented certain new and useful Improvements in Internal-Combustion Engines; and I do hereby declare the following to be a full, clear, and exact description of the invention, such as will enable others skilled in the art to which it appertains to make and use the same.

This invention relates to improvements in engines and more particularly to internal combustion engines of the opposed piston type.

An object of my present invention is to produce an engine having opposed reciprocating pistons arranged and adapted to impart a multiplicity of power strokes to an oscillating crank from which power may be transmitted to a work shaft such as a propeller shaft for ships, for example.

Another object of my invention is the production of an engine of the class described which can be readily installed in the place of an upon the foundation of the present marine type of steam engine, the same working conditions with regard to power, revolution, propeller and crank shafts and engine bed plate being maintained.

Another object of the present invention is to provide a readily assembled and efficient wrist pin construction for the lower piston and a rigid connection for the upper piston, together with adjustable guides therefor, whereby the strain upon the several parts can be more evenly distributed and the wear taken up.

With these and other objects in view the invention further consists in the construction and arrangement of the several parts hereinafter described and pointed out in the appended claims.

In the accompanying drawings, illustrating an embodiment of my invention as interconnected with the crank of a propeller shaft and whereon similar reference characters designate corresponding parts in the several views:—

Figure 1 is a vertical sectional view with parts in elevation through two of my improved engines showing led to the crank shaft of a propeller shaft.

Figure 2 is an enlarged detail vertical sec-

tional view through my improved engine taken at right angles to Figure 1;

Figure 3 is an enlarged horizontal sectional view on the line 3—3 of Figure 1;

Figure 4 is a detail plan view of the guides and connections for the upper piston; and

Figure 5 is a detail plan view of the locking nut for the piston wrist pin.

My present invention has been designed with a view to imparting oscillatory movement to a crank element from opposed reciprocating pistons of the multi-stroke type, and in turn utilizing said oscillations for rotating a ship's propeller shaft. In my present embodiment I have shown an engine of the opposed piston type wherein two power strokes of the piston are used to produce a single oscillation of the crank element through a predetermined arc.

It is desirable in marine propulsion to obtain a comparatively low propeller speed, and to develop the required horse power and efficiency from high speed internal combustion engines it is now usual to employ a reduction gear. In producing a multi-stroke internal combustion engine of the opposed piston type this complicated reduction gearing is not required, the engine and crank connections being constructed and interconnected with the propeller shaft in such a manner as to provide for the continuous rotation of the said propeller shaft by the oscillating movement of the crank element as produced by the multiplicity of power strokes of the opposed pistons.

The present design of internal combustion or oil engine is readily adaptable for use on ships from which the steam engine has been removed, a plurality of relatively small oil engines being arranged upon the bed plate or foundation on each side of the crank shaft and interconnected therewith as shown in Figure 1, for example. The relative distribution of the power and the saving of space by the use of a plurality of small engines are important factors, especially on ships or small engine rooms where the question of space is always foremost.

In Figure 1 I have illustrated a crank or propeller shaft 1 supported in main journal bearings 2 provided on pillow blocks or a plate 3, which latter may be secured to any

suitable foundation. Engine bed plates 4 and 5 are arranged adjacent the plate 3. The several parts described are of standard construction and with few exceptions constitute the usual foundations for the type of steam engines now in use.

My improved oil engines 6 and 7 are mounted upon these already installed foundations, after the steam engine has been removed. Each engine is connected with the propeller crank shaft 1, connecting rods 8 and 9 being interposed between the crank 1 and the oscillating web or crank element 10 of each engine as shown in Figure 1. The construction of each engine being the same, I will describe but one in detail, applying the same reference characters to corresponding parts of the other engine as will be understood.

The respective engines are comparatively small and compactly built, each comprising a cylinder 11, secured by bolts 12 to an intermediate supporting plate 13, which latter is mounted upon and secured to columns or uprights 14. The upper ends of the columns 14 are threaded and the plate 13 is secured by nuts 15 against the flanges 16 formed on said columns 14. Flanges 17 are provided on the base of the columns and bolts 18 serve to secure the columns to the foundation plates.

The cylinder 11 is provided at its upper end with an extension end or head 19 secured by bolts 20 to the cylinder 11, said extension forming a portion of the cylinder for the reciprocation of one of the pistons.

Mounted within the cylinder are pistons 21 and 22, arranged in opposed relation as shown and adapted to reciprocate inwardly and outwardly as will be understood. The action of the engine is preferably two cycle in operation, the air scavenging ports being shown at 23 and the exhaust ports at 24. The relative lengths of the pistons are sufficient to permit the proper opening and closing of these ports.

The upper piston 21 is of solid construction and is provided with the piston rod 25 formed integral therewith as shown. The piston rod 25 is connected to a crosshead 26 by means of the flange and nut construction 27, (see Figure 2.)

The cross-head 26 is provided with guide shoes 28 slidably mounted in guides 29. Wear plates 30 and threaded bolt and nut connections 31 are provided for adjusting the guide shoes and taking up wear.

Four guides 29 extend upwardly from the top of the cylinder, and bracing or tie rods 32 connect the upper ends of said guides with the cylinder supporting plate 13. The foregoing provides a strong and durable construction, the several parts being designed to receive maximum strains with minimum vibration, and provide for maxi-

mum smoothness in operation. It will be seen that the several parts can be readily aligned when setting the engine up. The location of the several parts on the outside of the engine permits inspection and repair with the least possible difficulty.

The upper piston 21 is connected to the crank 10 by means of connecting or reach rods 33. Bearings 34 provided on the upper end of the rods 33 encircle the projecting pins 35 carried by the crosshead; and bearings 36 provided on the lower end of said rods are fitted about the projecting pins 37 carried by the webs of the crank 10, (see Figure 2.)

The lower piston 22, and more especially the wrist pin connection therefor, is of novel construction. It is hollowed out as shown in Figures 1 and 2 and has a cylindrical bore extending transversely therethrough. The wrist pin 38 is of substantially cylindrical shape and is formed of complementary upper and lower sections 39 and 40, which extend diametrically across the piston and have their ends arranged in said bore.

The cylindrical end 41 of the connecting rod 42 is movably retained between the complementary sections of the wrist pin 38 as will now be described. Formed within the wrist pin section 39 is a recess 43 arranged and adapted to conform to the cylindrical shape of the end 41 of the rod 42. The upper portion of the cylindrical head 41 fits and moves within this recess as will be understood, the ends thereof being retained by the shoulders 44 at each end of the recess 43.

The complementary section 40 is split into two parts as shown to permit the rod 42 to extend into the piston head, the two portions 45 and 46 each being formed with a recess and shoulder construction 47, into and against which the lower portion of the cylindrical head 41 is movably fitted. It will be seen that the separated complementary sections 39 and 40 form bearings for the head 41, as well as constitute the wrist pin of the piston.

The means for retaining the wrist pin sections in position comprises a split ring 48 formed of threaded sections 49 and 50, arranged and adapted to be threaded into the lower internally threaded portion 51 of the piston 22. The ring sections 49 and 50 are held together by means of the dowel pin 52, and a tapered set screw 53, (see Figures 2 and 5). Recesses formed in the sections 49 and 50 cooperate to form a slot or elongated opening 54 through which the connecting rod 42 extends, and in which it swings. The ends of the opening may be tapered as shown in Figure 1, to permit the full swing of the rod 42 without interference as will be understood.

In practice the split nut is screwed into the threaded end 51 of the piston, up against the members 45 and 46 of the complementary section 40, thereby bringing the respective sections of the wrist pin against the cylindrical head 41. The tapered set screw 53 is now tightened until the split sections of the ring have been expanded sufficiently far to permit the threads thereof to securely interlock with the internal threads of the piston. By this construction advantages of assembly, inspection and repair are obtained, it being obvious that the wear incident to the strain upon the piston 22 can be readily taken up without dismantling the piston. A particularly free and easy motion of the piston and rod construction with very little friction, is also obtained by the foregoing construction.

The lower piston is connected to the crank 10 by means of the rod 42 hereinbefore mentioned. A bearing 55 is provided on the lower end of the rod 42, and is designed to encircle a crank pin 56. By referring to Figure 2 it will be seen that the pin 56 constitutes a portion of a staggered pin, the two adjacent portions 57 thereof being connected to the forked end 58 of the connecting rod 8 hereinbefore described. The crank pin connects the two web portions of the crank 10 as will be understood.

By referring to Figure 1 it will be seen that the respective crank pins 56 and 57 are located at different points on the circle indicated by the dotted lines A. The dot and dash arc B indicates the crank circle of the crank pin 37 interconnected with the upper piston 21. The radii of the respective crank pins 56 and 37 operatively connected with the opposed pistons 21 and 22, are different as shown, thereby providing for different distances of travel of the said pistons. The upper piston 21 has a relatively long travel incident to obtaining a full timed opening of the ports 24. The lower piston 22 has a shorter travel and controls the opening of the ports 23 through which the scavenging air enters, as will be understood.

The crank pins 57 about which the forked end 58 of the rod 8 is journaled, is offset with relation to a line drawn through the crank pins 37 and 56; and the engine shaft 59 as shown by the line C in Figure 1. The said crank pin 57 is however in alignment with the crank and propeller shaft 1, (see line D, Figure 1). The angle arrangement formed by the radius E of the crank pin 57 and the line D prevents the crank shaft 10 from rotating and permits the respective pistons to finish their compression and power strokes while the crank 1 is rotating continuously in one direction and with maximum efficiency. This angle arrangement also allows the connecting rod 8 to be made of relatively great length, and prevents the

axes of 59, 57 and 1 from coming into a straight line and forming a dead center.

The arc of oscillation of the crank 10 is shown by the dot and dash line B. Two full power strokes are obtained from the pistons during the movement of the crank 10 through one complete oscillation in this arc.

In operation, and with the pistons of the engines in the position shown in Figure 1, the pistons of engine 6 are just about finishing their inward or compression stroke, and the pistons of engine 7 have almost completed their power stroke. The next movement of the pistons in engine 6 will be outward. In travelling one power stroke, the crank 10 will move through one-half of the arc B to the point indicated by the letter F. The continued movement of the crank 10 through the remainder of the arc B in the direction of the arrow causes the pistons to return or move inward to produce the compression stroke. A full stroke of the piston has now been made, and as the crank 10 returns through its oscillatory path of travel another full stroke of the piston is similarly produced. Hence it will be seen that two complete strokes, or a multiplicity of strokes of the piston are required to oscillate the crank 10, which latter is in turn connected with and adapted to rotate a work shaft or crank a single revolution. In operation it will be noted that all of the inward strokes of the pistons are compression strokes and the angle formed between the radius E and line D is the result of the rotation of the crank 1, and is not caused by power developed between the pistons.

In arranging two engines, one upon each side of a crank or propeller shaft, it will be seen that the starting and finishing points of each engine are different, thereby preventing any tendency of the crank to stop on dead center, and to permit greater efficiency in the distribution of the power obtained from said engines.

In providing for an installation of relatively high horse power, a plurality of engines of small horsepower each are associated at intervals upon each side of the work or propeller shaft. The total horsepower of my small oil engines I prefer to equal the horsepower of the steam engine for which they are substituted. In ships, for example, oil engines are particularly advantageous, and in adapting my improved engine in the manner hereinbefore described, to the propeller shaft of a ship, greater economy in space, cost of maintenance and initial installation are possible.

My improved engine is not limited however to use on ships, as it can be readily arranged and constructed for other mobile or stationary uses. Changes in the proportion, size, arrangement and construction of the several parts may be made, and I do

not wish to be understood as limiting myself to the exact construction and application thereof herein disclosed.

I claim:

6. 1. In an internal combustion engine the combination with a cylinder of opposed pistons arranged therein, an oscillating crank shaft, and means connecting said opposed pistons with the oscillating crank shaft and arranged to cause multiplicity of power strokes of the pistons to be imparted to the crank shaft for every complete oscillation of the latter.
10. 2. In an internal combustion engine, the combination with a cylinder of opposed pistons arranged therein, an oscillating crank shaft, and rods connecting the opposite ends of said crank shaft to the respective opposed pistons and arranged to cause a multiplicity of power strokes of the pistons to be imparted to the crank shaft for every complete oscillation of the latter.
15. 3. In an internal combustion engine, the combination with a cylinder of opposed pistons arranged therein, an oscillating crank shaft having diametrically opposed cranks and crank pins, a connecting rod attached to one of said crank pins and to one piston, and another connecting rod connected to the other of said crank pins and to the other piston, said parts being arranged to cause a multiplicity of power strokes of the pistons to be imparted to the crank shaft for every complete oscillation of the latter.
20. 30. 4. In an internal combustion engine, the combination with a cylinder of opposed pistons arranged therein, an oscillating crank shaft provided with cranks and crank pins located at different radii from the center of the crank, and means including connecting rods attached to the crank pins and to the aforesaid pistons for transmitting a multiplicity of power strokes of the piston to the crank shaft for each complete oscillation of the latter.
25. 45. 5. In an internal combustion engine, the combination with a cylinder of opposed upper and lower pistons arranged therein, a cross head connected to said upper piston, connecting rods carried by said cross head, an oscillating crank shaft to one end of which the said connecting rods are attached and a connecting rod interposed between the lower piston and the other end of the oscillating crank, said parts being arranged to cause a multiplicity of power strokes of the pistons to be imparted to the crank shaft for each complete oscillation of the latter.
50. 60. 6. In an internal combustion engine, the combination with a cylinder of opposed upper and lower pistons arranged therein, a cross head rigidly connected to the upper piston, connecting rods carried by said cross head, an oscillating crank shaft having diametrically opposed cranks and crank pins,
55. 65. 7. In an internal combustion engine, the combination with a cylinder, of opposed pistons arranged therein, exhaust and air scavenging ports arranged in the cylinder near its opposite ends and controlled by said pistons, an oscillating crank shaft having diametrically opposed cranks and crank pins, one of said crank pins being arranged nearer the axis of the shaft than the other of said crank pins, means connecting one of said pistons with the crank pin of said shaft which is located the greatest distance from the axis of rotation of the latter, for producing a relatively long piston travel, and means connecting the other piston with the other crank pin of said shaft for causing a relatively short piston travel, said parts being arranged to cause a multiplicity of power strokes of the pistons to be imparted to the crank shaft for every complete oscillation of the latter.
8. In an internal combustion engine, the combination with a cylinder having opposed upper and lower pistons arranged therein, an oscillating crank shaft adapted to receive a multiplicity of power strokes of the piston for every oscillation thereof, means connecting the upper piston with one end of the oscillating crank, means connecting the lower piston with a diametrically opposite end of said crank, and means including a crank and connecting rod interconnected with the aforesaid oscillating crank for obtaining continuous rotary motion.
9. In an internal combustion engine, the combination with a cylinder having opposed upper and lower pistons arranged therein, an oscillating crank shaft adapted to receive a multiplicity of power strokes of the piston for every oscillation thereof, means connecting the upper piston with one end of the oscillating crank, means connecting the lower piston with a diametrically opposite end of the crank, and means connected to the oscillating crank for imparting continuous rotary motion.
10. In an internal combustion engine, the combination with a cylinder having opposed pistons arranged therein, an oscillating crank shaft arranged and adapted to receive a multiplicity of power strokes of the said opposed pistons for every complete oscillation of said crank, means connecting the opposed pistons to the oscillating crank, and means for transmitting continuous rotary motion from said oscillating crank shaft.

11. In an internal combustion engine, the combination with a cylinder having opposed pistons arranged therein, an oscillating crank shaft arranged and adapted to receive a multiplicity of power strokes of the said opposed pistons for every complete oscillation of said crank, means connecting the opposed pistons to the oscillating crank, a revolvable crank shaft, and means including a connecting rod interposed between and connected to the aforesaid revolving and oscillating crank shafts for transmitting continuous rotary motion from the oscillating crank shaft to the revolvable crank shaft.
12. In an internal combustion engine, the combination with a cylinder having opposed pistons arranged therein, an oscillating crank shaft arranged and adapted to receive a multiplicity of power strokes of the said opposed pistons for every complete oscillation of said crank, means connecting the opposed pistons to the oscillating crank, a revolvable shaft, and means for transmitting continuous rotary motion to the said revolvable shaft from the aforesaid oscillating crank shaft.
13. In an internal combustion engine, the combination with a cylinder of opposed pistons arranged therein, an oscillating crank shaft provided with substantially diametrically oppositely disposed cranks and crank pins, means for connecting said crank pins to the respective aforesaid opposed pistons, another crank pin provided on said oscillating crank, and means connected to the last mentioned crank pin for transmitting continuous rotary motion from the aforesaid oscillating crank shaft.
14. In an internal combustion engine, the combination with a cylinder of opposed pistons arranged therein, an oscillating crank shaft provided with cranks and crank pins located at different radii from the center of the crank and diametrically opposite each other, means for connecting said crank pins to the respective aforesaid opposed pistons for causing the latter to move differentially, another crank pin located at a radius equal to one of the aforesaid crank pins, but having its axis offset relatively to the axis of the last mentioned crank pin, and means connected to the last mentioned crank pin for transmitting continuous rotary motion from the aforesaid oscillating crank shaft while preventing the oscillating shaft from rotating.
15. In an internal combustion engine, the combination with a cylinder having upper and lower opposed pistons, an oscillating crank connected to said pistons and adapted to receive a multiplicity of power strokes of the pistons for every complete oscillation of said crank, a cross head for said upper piston, a rigid connection between said upper piston and cross head, a connecting rod interposed between said cross head and said oscillating crank shaft, and a swinging connection interposed between the lower piston and the oscillating crank.
16. In an internal combustion engine, a cylinder, opposed pistons arranged in said cylinder, an oscillating crank shaft having diametrically oppositely disposed cranks and crank pins, a rod connecting one of said pistons to one of said crank pins, a second rod connecting the other piston to the other one of said crank pins, said parts being constructed and arranged to permit one of said crank pins to travel in a substantially semicircular path at one side of a plane drawn through the axis of rotation of the shaft and the other crank pin to travel in a substantially semicircular path arranged at the opposite side of said plane, a rotating crank shaft, and means connecting one of the cranks of the rotating shaft to one of the crank pins of the oscillating shaft, said parts being arranged to cause a multiplicity of power strokes to be imparted to the oscillating shaft for each complete oscillation of the latter.
17. An engine as claimed in claim 16 in which the means connecting the rotating shaft to the oscillating shaft comprises a connecting rod of a length sufficient to prevent the oscillating shaft from rotating.
18. An engine as claimed in claim 16 in which one of said crank pins is arranged at a greater distance from the axis of rotation of the oscillating shaft than the other one of said crank pins.

In testimony whereof I affix my signature, in presence of two subscribing witnesses.

CHARLES REINEKE.
